UNITED STATES PATENT OFFICE.

HARRY B. LATINA, OF EAST ST. LOUIS, ILLINOIS, ASSIGNOR TO RAWLINGS MANUFACTURING COMPANY, OF ST. LOUIS, MISSOURI, A CORPORATION OF MISSOURI.

BASEBALL MITT.

Application filed May 7, 1924. Serial No. 711,611.

To all whom it may concern:

Be it known that I, HARRY B. LATINA, a citizen of the United States, residing at East St. Louis, Illinois, have invented a certain new and useful Improvement in Baseball Mitts, of which the following is a full, clear, and exact description, such as will enable others skilled in the art to which it app pertains to make and use the same.

10 This invention relates to baseball mitts of the kind that are used by catchers and first basemen and which consists of a relatively thick pad provided on its back or rear side with a hand portion that comprises pockets 15 for receiving the thumb and fingers of the user's hand.

In the conventional baseball mitt the hand portion on the rear side of the pad is provided with an adjustable strap that extends 20 transversely of the user's wrist so as to retain the mitt in operative position on the user's hand. Unless said wrist strap is fairly tight, there is great danger of the mitt dropping off or flying off the user's 25 hand accidentally at a time when such an accident might be the deciding factor of a game of baseball, but many baseball players object to having the mitt strapped tightly in position, because it prevents the 30 mitt from being thrown off or dropped quickly in the event the user desires to have his hand free and unencumbered by a mitt. The result is that the majority of baseball players adjust the wrist strap of the mitt in 35 such a way that the mitt can be intentionally dropped quickly, notwithstanding the fact that the loose adjustment of the wrist strap may result in the mitt dropping off accidentally at a critical point in the game.

40 The main object of my invention is to provide a baseball mitt which is constructed in such a manner that it will be loose enough on the user's hand to permit it to be dropped quickly or thrown off intentionally, but will 45 be combined with the user's hand in such a way when the mitt is in use that there is no danger of its dropping off or being thrown off accidentally.

To this end I propose to provide the hand 50 portion of a baseball mitt with one or more loops arranged in such a way that the thumb or a finger of the user's hand will project through same and exert sufficient pressure on said loop or loops to eliminate

the possibility of the mitt dropping off accidentally, even though the wrist strap is loose.

Another object of my invention is to provide a baseball mitt in which the hand portion of the mitt is constructed in such a manner that the hand of the user naturally assumes such a position, during the operation of catching a ball, that the palm of the hand will be held slightly spaced away from the part of the mitt against which a caught ball strikes, thereby reducing the liability of the user's palm being bruised or injured when the mitt is used to stop a swift ball thrown with considerable force.

Figure 1 of the drawings is a perspective view of a baseball mitt constructed in accordance with my invention.

Figure 2 is a perspective view of the front piece of the hand portion of the mitt to which the pad is laced.

Figure 3 is a perspective view of the mitt shown in Figure 1, with the back piece of the hand portion broken away to show the thumb loop and some of the finger stops or abutments.

Figure 4 is a top plan view of the front piece of the hand portion, illustrating how the thumb and finger loops are permanently connected to same; and

Figure 5 is a top plan view, partly broken away, of a mitt constructed in accordance with my invention and equipped with finger stops or abutments of slightly different construction from those used in the mitt illustrated in Figures 1 to 4.

In the drawings A designates a pad that forms the front side of a baseball mitt and B designates a piece of leather or other suitable material of the same outline as said pad to which said pad is secured by a lacing 1 or in any other suitable manner. A hand portion is arranged on the back or rear side of the pad A for receiving the user's hand, and while the particular details of construction of said hand portion are immaterial so far as my invention is concerned, it will usually comprise a front piece, formed by the piece B to which the pad is laced, a back piece C that comprises thumb and finger portions which are secured by 105 stitches to the piece B in such a way as to form pockets for the thumb and fingers of the user's hand, and an adjustable wrist

strap D that extends transversely of the user's wrist. In order to eliminate the possibility of the mitt dropping off accidentally when the wrist strap D is adjusted loose enough to permit the mitt to be dropped quickly or thrown off intentionally by a quick movement of the user's arm, I have equipped the mitt with a thumb loop E through which the user's thumb projects, as shown in Figure 2, when the mitt is in use. Said loop E is arranged inside of the thumb pocket of the hand portion, and notwithstanding the fact that said loop is large enough to permit the user's thumb to slip into and out of same easily, it constitutes a very efficient means for preventing the mitt from dropping off accidentally, due to the fact that a slight contraction or flexing of the user's thumb causes said loop to be gripped tightly enough to prevent the thumb from accidentally pulling out of same. In most instances the mitt will be equipped with a similar loop F arranged inside of the pocket of the hand portion that receives the little finger of the user's hand, so as to obtain a more perfect balance of the mitt on the user's hand, but both of said loops are not absolutely essential, although it is preferable to construct the mitt in this way.

It is immaterial how the loops E and F are secured inside of the pockets in which they are positioned, but I prefer to make said loops adjustable and form each loop 35 from a strip of leather or other suitable material that is permanently secured at one end by stitches 2 to the front piece B of the hand portion, as shown in Figure 4, the strip from which the loop is formed being doubled 40 over, as shown in Figure 3, so as to form top and bottom pieces joined together by a connecting portion located at the inner end of the loop, the free end of the top piece projecting outwardly through a slot 3 in the 45 back piece C of the hand portion. Due to the fact that each of said loops comprises a bottom piece, a top piece and a connecting portion for said top and bottom pieces disposed so that the inner side of the user's 50 thumb or little finger will naturally exert pressure on said connecting portion in the normal operation of using the mitt, there is little liability of the mitt accidentally dropping off the user's hand. In the mitt shown 55 in Figures 1 to 4 the free ends of the loops E and F are detachably connected to the front piece B of the hand portion by conventional button snaps, and in order that the size of said loops may be varied, each 60 loop is provided with a socket member 4 that is adapted to co-operate with a plurality of buttons 5 arranged different distances from the slot 3 in the back piece C of the hand portion through which the free end of the 65 loop extends. A loop or loops of the kind

described adds greatly to the efficiency of a baseball mitt, as they permit the wrist strap of the mitt to be adjusted in a loose condition without danger of the mitt dropping off accidentally at a critical time when such an accident might result in the winning or losing of a game of baseball.

As previously stated, another object of my invention is to provide a baseball mitt which is so constructed that the palm of the user's hand will be held spaced away slightly from the part of the mitt against which a caught ball strikes. This feature of my invention is separate and distinct from the feature previously described, to wit, the loop or loops in the hand portion, and can be used independently of said loops or in conjunction with same. I accomplish this desirable result by equipping certain of the finger pockets of the hand portion with stops or abutments G arranged far enough from the ends of said pockets to make it necessary for the user to cup his hand by bending or contracting his fingers during the operation of catching a ball. In the mitt shown in Figures 1 to 4, inclusive, the finger stops or abutments G are formed by pieces of leather or other suitable material secured by stitches, or in any other way, to the front piece B of the hand portion of the mitt and arranged at such points that the tips of the user's fingers can be pressed against same by bending or flexing the fingers sufficiently to cup the hand. The main function of the finger stops or abutments G is to insure the user cupping his hand sufficiently to hold the palm away from the portion of the mitt against which a caught ball strikes, thus eliminating the possibility of the user's palm being bruised, but said finger stops or abutments also insure the user's fingers obtaining such a firm grip or hold on the mitt that the user has perfect control of the mitt. Preferably, the upper ends of the pieces of leather that constitute the finger stops G are doubled or folded over, as shown more clearly in Figure 4, so as to produce members in the finger pockets of the hand portion that are high enough or deep enough to serve as abutments against which the tips of the user's fingers can be pressed tightly by cupping the hand.

In Figure 5 of the drawings I have illustrated a baseball mitt that embodies all of the desirable features and characteristics of the mitt shown in Figures 1 to 4, but equipped with finger stops or abutments of slightly different construction. The pockets that receive the thumb and little finger of the user's hand are provided with loops E and F of the kind previously described and the three finger pockets arranged between the thumb pocket and little finger pocket are equipped with finger stops or abutments

formed by a member G' that extends transversely of said finger pockets and which is arranged far enough away from the ends of said pockets to insure the user's hand 5 assuming a cupped condition when the tips of the fingers are pressed against said member G'. Preferably, the member G' consists of a strip of leather or other suitable material permanently connected at one end 10 by stitches, or in any other suitable way, to the front piece B of the hand portion adjacent the little finger pocket and laced through slits 6 in the other three finger pockets of the hand portion, the free end 15 of said strip being detachably and adjustably connected to the front piece B of the hand portion either by a buckle or by a socket member 7 on said strip that co-operates with a plurality of spaced buttons 20 7^a on the front piece B of the hand portion of the mitt. The member G' extends transversely of the finger pockets, as shown in Figure 5, and when the mitt is in use, the tips of the user's fingers are drawn 25 downwardly into engagement with said member, thereby enabling the user to obtain a firm grip or hold on the mitt and insuring the palm of the user's hand being spaced slightly away from the pad on the 30 front side of the mitt.

Having thus described my invention, what I claim as new and desire to secure by Letters Patent is:

1. A baseball mitt, comprising a pad that 35 constitutes the front portion of the mitt, a hand portion combined with said pad, and loops in said hand portion through which the thumb and little finger of the user's hand are adapted to be inserted each of said loops 40 comprising a top piece, a bottom piece and a connecting portion for joining said pieces disposed so that the part of the user's hand positioned in the loop will naturally exert pressure on said connecting portion when 45 the mitt is in use.

2. A baseball mitt, comprising a pad that constitutes the front portion of the mitt, a hand portion on the back side of said pad provided with pockets for receiving the 50 thumb and fingers of the user's hand, and loops in the thumb and little finger pockets, for the purpose described.

3. A baseball mitt, comprising a pad that constitutes the front portion of the mitt, a 55 hand portion on the back side of said pad provided with pockets for receiving the thumb and fingers of the user's hand, loops in the thumb and little finger pockets, for the purpose described, and means for enabling said loops to be adjusted.

4. A baseball mitt, comprising a pad that constitutes the front portion of the mitt, a hand portion on the back of said pad formed 60 by a front piece to which the pad is detachably connected and a back piece provided

with a plurality of pockets, and loops in the thumb pocket and little finger pocket, each provided with a top piece, a bottom piece and a connecting portion on which the part of the user's hand surrounded by the loop 70 naturally exerts pressure in a way to prevent the mitt from accidentally dropping off the hand.

5. A baseball mitt, comprising a pad that constitutes the front portion of the mitt, a 75 hand portion on the back of said pad formed by a front piece to which the pad is detachably connected and a back piece provided with a plurality of pockets, and loops in some of said pockets formed from strips of 80 material permanently connected at one end to the front piece of the hand portion and arranged with their free ends projecting outwardly through slots in the back piece of the hand portion.

6. A baseball mitt, comprising a pad that constitutes the front portion of the mitt, a hand portion on the back of said pad formed by a front piece to which the pad is detachably connected and a back piece provided 90 with a plurality of pockets, loops in some of said pockets formed from strips of material permanently connected at one end to the front piece of the hand portion and arranged with their free ends projecting outwardly through slots in the back piece of the hand portion, and means for adjustably securing the free ends of said strips to the front piece of the hand portion.

7. A baseball mitt, comprising a pad that 100 constitutes the front portion of the mitt, a hand portion on the back of said pad provided with pockets for receiving the thumb and fingers of the user's hand, loops in the thumb pocket and little finger pocket, and 105 means arranged in some of the finger pockets against which the tips of the user's fingers are adapted to be pressed so as to hold the user's hand in a cupped condition.

8. A baseball mitt, comprising a pad that 110 constitutes the front portion of the mitt, a hand portion on the back of said pad provided with finger pockets, and a transversely-disposed member laced through slots in said pockets and adapted to serve as stops or abutments against which the tips of the user's fingers are pressed when the glove is in use.

9. A baseball mitt, comprising a pad that 115 constitutes the front portion of a mitt, a hand portion on the back of said pad provided with finger pockets, a transversely-disposed abutment member laced through slits in some of said pockets and having one of its ends permanently connected to the 120 hand portion of the mitt, and means for adjustably securing the other end of said member to the hand portion of the mitt, said abutment member being arranged under the 125 user's fingers and disposed so as to cause the 130

user's hand to assume a cupped condition when the tips of the fingers are pressed against said member.

10. A baseball mitt, comprising a pad that constitutes the front portion of the mitt, a hand portion on the back of said pad provided with finger pockets and a thumb pocket, loops in the thumb pocket and the

little finger pocket, and an abutment member arranged transversely by the pockets intermediate the thumb and little finger pocket against which the tips of the user's fingers are adapted to be pressed during the operation of catching a ball. 10

HARRY B. LATINA.
